CLAIM

We claim the ornamental design for a fused distribution block, as shown and described.

DESCRIPTION

FIG. 1 is a left-front perspective view of a fused distribution block showing a first embodiment of our new design;

FIG. 2 is a top plan view of FIG. 1;

FIG. 3 is a bottom plan view of FIG. 1;

FIG. 4 is a left side elevation of FIG. 1. The right side is a mirror image thereof;

FIG. 5 is a rear elevation of FIG. 1;

FIG. 6 is a front elevaton of FIG. 1;

FIG. 7 is a left-front perspective view of a second embodiment of a fused distribution block showing our new design;

FIG. 8 is a top plan view of FIG. 7;

FIG. 9 is a bottom plan view of FIG. 7;

FIG. 10 is a left side elevation of FIG. 7. The right side is a mirror image thereof;

FIG. 11 is a front elevation of FIG. 7; and,

FIG. 12 is a rear elevation of FIG. 7.

The broken line showing of the environment is for illustrative purpose only and forms no part of the claimed design.
